Primary Examiner — Kelley Donnelly(74) *Attorney, Agent, or Firm* — Lexyoume IP Meister, PLLC.(57) **CLAIM**

The design for a showcase frame extrusion, as shown and described.

DESCRIPTION

FIG. 1 is a top and right side perspective view of a showcase frame extrusion showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a bottom and left perspective view of the showcase frame extrusion shown of FIG. 1; and,
FIG. 9 is a front sectional view showcase frame extrusion shown in its position of use, taken along a line 6-6 of FIG. 6. The broken lines are illustrative purpose only and form no part of the claimed design.
